FOLDING METAL AWNING

Joshua Thomas Kitching, Pleasantville, N. J.

Application June 26, 1936, Serial No. 87,520

1 Claim. (Cl. 156—43)

This invention relates to folding metallic awnings and has for the primary object the provision of a device of this character which will be extremely simple in construction and easy to adapt to a building and may be either manually actuated or power driven and when folded or collapsed will lie substantially within a casing, the latter and the awning when folded will not project any further beyond the face of a building than 10 awnings now employed.

With these and other objects in view, this invention consists in certain novel features of construction, combination and arrangement of parts to be hereinafter more fully described and 15 claimed.

For a complete understanding of my invention, reference is to be had to the following description and accompanying drawings, in which

Figure 1 is a front elevation illustrating an 20 awning constructed in accordance with my invention and showing the same collapsed.

Figure 2 is a fragmentary transverse sectional view showing the awning collapsed and adapted to a building.

Figure 3 is a vertical sectional view illustrating 25 the awning in an extended position.

Figure 4 is a fragmentary perspective view, partly in section, showing one of the awning sections.

Figure 5 is a detail sectional view showing the 30 power drive for the awning.

Referring in detail to the drawings, the numeral 1 indicates a collapsible metallic awning composed of a series of telescopic sections 2 of substantially U-shape and said sections being pivotally connected, as shown at 4. One of the end sections has formed at its free edge a trough 5 for the purpose of catching water drained from the awning when extended to direct the water 40 towards the face or wall of a building to which the awning is adapted. The collapsed awning or sections thereof slide one within the other and to bring about collapsing all sections except one of the end sections has beading 6 so 45 that as the sections progressively move inwardly of each other said sections contact the beadings and bring about a complete collapsing of the awning. All sections except one of the end sections have beadings 7 and 8 which beadings contact during the unfolding of the awning to prevent complete separation of the sections.

A housing 9 of the general shape of the sections of the awning is suitably secured to a building and has a compartment 10 opening out-

wardly through the front thereof in which the sections as they fold in telescopic relation may move to become substantially confined within the compartment. Thus it will be seen that when the awning is folded or collapsed and within the 5 compartment 10 the device in entirety will not project any further from the face of the wall of a building than is customary with awnings now in use. Gear compartments 11 are formed in the casing in which are located drums 12 secured to a shaft 13 extending into both compartments. The drums have secured and wound thereon flexible elements 14 secured to one of the end sections of the awning adjacent the gutters thereof. By rotating the shaft 13 in one 15 direction, the awning may be collapsed into the casing and by rotation of the shaft in an opposite direction the awning may be moved into extended position. The shaft 13 may be either manually rotated or by power. A gear box 15 20 is secured to the casing with the shaft 13 extending therethrough. A worm gear 16 is secured to the shaft within the gear box 15 and meshes with a worm 17. The worm 17 may be connected to an electric motor 18 suitably mounted to the building or may be connected to a shaft 19 extending to a gear box 20 in which are located meshing beveled gears 21, one secured to the shaft 19 and the other to a crank 25 handle 22. The crank handle is located in convenient reach of a person standing adjacent the awning so that the latter may be raised and lowered, as desired.

Having described the invention, I claim:

A metallic awning comprising a plurality of 35 telescopic sections of inverted U-shape, the inner section having its outer edge bent to form a gutter extending the full length thereof and the upper edge of said inner section being bent in the form of an outwardly extending bead, and the 40 remaining overlying sections having inwardly extending beads on their lower edges and outwardly extending beads on their upper edges, inner and outer beads of successive sections engaging to maintain the sections in cooperative 45 engagement when in extended position, said overlying sections also having inwardly extending beads formed on their upper edges providing stops against which the upper edges of adjacent sections engage when the sections are in 50 collapsed position, and means for extending and collapsing the sections.

JOSHUA THOMAS KITCHING.
